UNITED STATES PATENT OFFICE

ROBERT M. MILLER, OF MONTGOMERY, PENNSYLVANIA

DESK

Application filed September 25, 1931. Serial No. 565,157.

This invention relates to typewriter desks and is more especially an improvement upon the structure disclosed in Patent 1,725,816, issued to me on August 27, 1929.

5 One of the objects is to provide the desk with a hinged drop-leaf to which the typewriter is adapted to be connected said leaf being equipped with a supporting leg foldable backwardly and upwardly behind the 10 leaf when dropped.

A further object is to provide a substantial supporting leaf or shelf for a typewriter or the like which can be quickly moved into or out of operative position, it being mounted 15 both to swing and slide relative to its housing, there being a runner connected to the leaf for supporting it in its lowermost position for sliding movement.

With the foregoing and other objects in 20 view which will appear as the description proceeds, the invention resides in the combination and arrangement of parts and in the details of construction hereinafter described and claimed, it being understood that changes 25 in the precise embodiment of the invention herein disclosed may be made within the scope of what is claimed without departing from the spirit of the invention.

In the accompanying drawings the pre- 30 ferred form of the invention has been shown.

In said drawings:

Figure 1 is a vertical longitudinal section showing the leaf extended for use.

Figure 2 is a front elevation thereof.

35 Figure 3 is a section on line 3—3, Figure 1.

Figure 4 is a vertically longitudinal section showing the leaf lowered and housed, said leaf and its slide being shown in elevation.

40 Figure 5 is a section on line 5—5, Figure 4.

Referring to the figures by characters of reference, 1 designates a suitably constructed housing which can constitute a pedestal of a desk or can comprise a desk complete in itself.

45 A laterally swinging door 2 serves to close the front of the housing and carries a block 3 on its inner surface provided with a latch 4 for the purpose hereinafter stated.

Spaced superposed guide strips 5 and 6 are 50 arranged in pairs on the inner surfaces of

the sides of the housing adjacent to the top thereof and guide rails 7 are attached to the lower strips 5 and partly lap the slots 8 between the strips.

A slide 9 is interposed between rails 7 and 55 has angle plates 10 secured to the sides thereof. These plates bear down on the rails 7 and extend back of them between strips 5 and 6. Thus the slide is held assembled with the housing but can be moved freely toward or 60 from the door 2.

Extending under and hinged to the back edge of slide 9 as indicated at 11 is a leaf or shelf 12 having sockets 13 for the reception of dowels 14. These dowels extend downwardly 65 from the front portion of the slide and are adapted to be received by the sockets 13 when the leaf or shelf is elevated, thereby relieving the hinges 11 from side strains.

Transverse guide cleats 15 are secured on 70 the leaf and located between them is a slidable board 16 to which a typewriter or the like can be fastened. The board is held against displacement by retaining strips 17 secured on cleats 15 andlapping the board. 75

A broad strip 18 is secured within the bottom portion of the housing 1 and extends 80 backwardly from the bottom of the door opening. This strip constitutes a rail and is provided near its front end with a notch 19. The back end of the strip extends between vertically disposed blocks 20 the front edges 21 of which are curved rearwardly and upwardly.

Secured to the bottom of shelf or leaf 12 85 is a runner 22 which may be in the form of a triangular block centrally located, on the shelf or leaf. This block is so proportioned that when the shelf or leaf 12 is swung downwardly the bottom edge of the block will rest flat on strip 18. The forked end of a leg 23 straddles the block and is pivoted thereto as shown at 24. The other end of the leg has a projecting tongue 25.

When it is desired to use the leaf or shelf 95 12 the door 2 is swung open and the leaf will be found in the housing in an inclined position with runner 22 bearing on strip 18 and the leg 23 extended upwardly back of the inclined leaf. A handle 26 on the leaf is then 100

used for pulling the leaf upwardly and outwardly beside the open door 2 and at the same time the slide 9 will move forwardly. The back end of leg 23 will drag along blocks 20 and strip 18 until tongue 25 arrives over recess 19 whereupon it will drop into the recess and hold the leaf 12 in operative position. Door 2 can then be swung against the side of the leaf 12 to bring block 3 thereunder and allow the spring catch to snap into engagement with the bottom surface of the leaf.

The structure is now ready for use and the board 16 can be slid to any position necessary to properly place the supported machine. When the structure is to be closed, the leaf 12 is pulled upwardly slightly to withdraw tongue 25 from notch 19 and disengage the leaf from latch 4. The door is swung laterally to remove the block 3 from under the leaf and the leg 23 is pressed backwardly with the foot. Thereafter the leaf 12 is lowered and pushed backwardly. The leg 23 will slide along strip 18 and thence upwardly along the edges 2 of blocks 20.

The runner 22 will slide along strip 18 and when the parts are brought to their innermost positions the door can be closed.

For the purpose of reducing friction roller bearings 27 can be placed on the runner 22 and on the strip 18. Wear strips 28 of metal can also be attached to the sides of the guide strips 6 for lapping the sliding member thereunder, thereby reducing friction.

What is claimed is:

1. The combination with a housing having a door opening, of a slide therein, means for guiding the slide for movement toward and from the opening, a drop leaf hingedly connected to the slide and movable therewith, a runner carried by the leaf, a leg pivotally connected to the runner, a rail in the housing for sliding engagement by the leg and runner, and cooperating means on the leg and rail for holding the leg in position to support the leaf and runner in elevated positions.

2. The combination with a housing having a door opening, of a slide therein, means for guiding the slide for movement toward and from the opening, a drop leaf hingedly connected to the slide and movable therewith, a runner carried by the leaf, a leg pivotally connected to the runner, a rail in the housing for sliding engagement by the leg and runner, and means extending from the rail for elevating one end of the leg during the sliding movement of the runner in one direction.

3. The combination with a housing having a door opening, of a slide therein, means for supporting the slide for movement toward and from the opening, a drop leaf hingedly connected to the slide and movable therewith, a runner carried by the leaf, a leg pivotally connected to the runner, a rail in the hous-

ing for sliding engagement by the leg and runner, and means extending from the rail for elevating one end of the leg during the sliding movement of the runner in one direction, and cooperating means on the leg and rail for holding the leg in position to support the leaf and runner in elevated positions.

4. The combination with a housing having a door opening, of a slide therein, means for guiding the slide for movement toward and from the opening, a drop leaf, means for connecting the leaf to the slide for downward movement about an axis extending transversely of the opening, a runner carried by the leaf, a rail in the housing for engagement by the runner when the leaf is lowered and means cooperating with the rail and runner for holding the leaf in raised position.

5. The combination with a housing, of a drop leaf, a support therefor slidably mounted in the housing, a runner fixed to the leaf, a leg hingedly connected at one end to the runner and free at its other end, and means cooperating with the leg for supporting the drop leaf and runner in elevated position when slid to one limit of its movement.

In testimony that I claim the foregoing as my own, I have hereto affixed my signature.

ROBERT M. MILLER.
